UNITED STATES PATENT OFFICE.

THOR W. PETERSEN, OF CHICAGO, ILLINOIS, ASSIGNOR, BY MESNE ASSIGNMENTS, TO
J. LUTHER PEACOCK, OF CHICAGO, ILLINOIS.

VENDING-MACHINE.

1,219,768.

Specification of Letters Patent. Patented Mar. 20, 1917.

Application filed August 11, 1915. Serial No. 44,923.

To all whom it may concern:

Be it known that I, THOR W. PETERSEN, a citizen of the United States, and a resident of the city of Chicago, county of Cook, and 5 State of Illinois, have invented certain new and useful Improvements in Vending-Machines, of which the following is a specification.

My invention relates to improvements in 10 vending machines especially adapted for vending postage stamps, and has for its object the provision of an improved machine of this character which is of simple construction and reliable in operation.

15 The invention consists in the combinations and arrangements of parts hereinafter described and claimed.

The invention will be best understood by reference to the accompanying drawings 20 forming a part of this specification, and in which,

Figure 1 is a face view of a machine embodying my invention,

Fig. 2, a side elevation of the same,

25 Fig. 3, a section taken on line 3—3 of Fig. 1,

Fig. 4, a perspective view of one of the envelopes in which the stamps to be sold are inclosed,

30 Fig. 5, an enlarged partial face view of the machine with the front plate thereof removed and showing the coin chutes employed in the machine,

Fig. 6, a top plan view of the machine 35 with the cover removed,

Fig. 7, a longitudinal vertical section of the machine,

Fig. 8, a transverse section of the machine,

40 Fig. 9, another transverse section of the machine,

Fig. 9^a, a detail view illustrating parts shown in Fig. 9,

Fig. 10, a detail view of a bracket employed in the construction, and

45 Fig. 10^a, a bottom plan view of the machine.

The preferred form of construction, as 50 illustrated in the drawings, comprises a suitable casing 11 detachably mounted on a hollow base 12 having a removable money drawer 13 therein. Vertical partitions 14 are arranged in casing 11 dividing said casing into a plurality of envelop containing

compartments or hoppers 15, 16, 17 and 18, 55 the hoppers 15, and 16 being arranged in a coöperating pair with a space 19 between them, and the hoppers 17 and 18 being arranged in a coöperating pair with a space 20 between them, the hoppers 15 and 16 being designed for dispensing a nickel or five cents' worth of stamps, and the hoppers 17 and 18 being designed for dispensing ten cents' worth of stamps.

Slide rods 21, 22, 23 and 24 are arranged 60 centrally under the hoppers 15, 16, 17 and 18 respectively, said rods being slidable through the front wall of casing 11 and through a depending flange 25 formed on the bottom plate 26 of casing 11, each of said slide rods 70 being provided with an operating handle 27 at the front of the machine. Each of the slide rods carries an upwardly and forwardly extending feed member 28 secured to the rear of the rod and having an upwardly off-set portion 29 located at its forward end. Each of the feeding members 28—29 operates through a corresponding opening 30 formed in the front of casing 11 and a depressible spring guard 31 is provided 75 for each of the openings 30 and arranged to be depressed by forward movement of the corresponding feed member 28 to permit passage of the same but preventing insertion of a wire or other tool through 80 the opening 30. A vertically adjustable feed plate 32 constitutes the lower forward portion of each of the hoppers, said feed plate carrying the corresponding partitions 85 14 and being vertically adjustable to adjust the same nicely to permit of envelopes containing the stamps to pass thereunder. The stamps are inserted in envelopes 33 having depending flaps 34 at their forward edges adapted to be engaged by off-set portion 90 29 of the corresponding feed members 28 to feed the envelopes outwardly through the corresponding openings 30. The envelopes are filled with stamps of the proper denomination and are arranged in piles in 100 the different stamp hoppers with the flaps 34 arranged on their under forward sides, and a suitable weight is placed on each pile to press the same downwardly. The arrangement is such that upon forward movement 105 of any of the handles 27, the corresponding feed member 28—29 engages under the flap 34 of the lowermost envelop in the corre-

sponding stamp hopper and projects said envelop outwardly through the corresponding opening 30 to permit of its removal, the corresponding feed plate 32 preventing disturbance of the uppermost envelops, as will be readily understood.

Each of the slide rods 21, 22, 23 and 24 carries a bracket 35, the brackets 35 on the rods 21 and 22 projecting toward each other and lying immediately adjacent, while the brackets on rods 23 and 24 similarly project toward each other. Each of the brackets 35 is provided with a guide slot 36 running on a headed stud 37. Each of the adjacent brackets 35 is provided with a semi-circular notch 38 registering with a corresponding notch in the adjacent bracket 35 and a pivoted finger 39 is provided with a cylindrical stud 40 operating in said notches, the arrangement being such that upon movement of either of the adjacent brackets 35, the pin 40 will be shifted over into the other notch, but simultaneous movements of adjacent brackets are prevented owing to the fact that the stud 40 must lie wholly in one of the notches 38 before the other bracket can be moved.

Each of the brackets 35 is normally held in retracted position by means of a spring 41 connected at its forward end to a lug 42 on the bottom of said bracket and to a corresponding lug 43 depending from bottom plate 26, as best indicated in Fig. 10^a. Each of the brackets 35 is also provided with a depending ratchet bar 44 coöperating with a pivoted double-acting pawl 45 controlled by a spring 46, the arrangement being such that the pawl 45 will permit movement of the corresponding bracket 35 in either direction, but such movement having been started, it must be continued until the pawl runs off of the opposite end of the ratchet bar, this arrangement thus compelling complete movements of the brackets 35 after such movements have once been started. By this means, the continued successive operations of the brackets and slides is prevented upon insertion of a single coin, since provision is made, as will be more fully described hereinafter, whereby complete forward movement of one of the brackets releases and discharges the coin which renders such movement possible so that repetition is impossible.

Mounted on each of the brackets 35 is a cam member 47 having a notch 48 therein coöperating with a lug 49 on a vertically swinging arm 50 pivoted in the casing at 51, as best shown in Figs. 8 and 9. Each of the arms 50 carries a forwardly extending stud 52 provided with a lug 53 projecting through a suitable opening into a coin space 54 formed between the front wall of casing 11 and the front plate 55, as indicated. Suitable ribs or guides 56 and 57

are provided in coin space 54 in position to form downwardly converging coin chutes 58, said coin chutes leading from the coin entry slots 59 formed in the top of plate 55. These coin chutes 58 are arranged in pairs, one pair coöperating with the two nickel slots, and the other pair coöperating with the two dime coin slots, but each serving to direct a coin deposited therein to a position in which it will be supported by the corresponding lug 53. Fig. 5 illustrates in dotted lines the position of a nickel 60 deposited in one of the coin chutes and brought to rest by the corresponding lug 53. In this position, the suspended nickel rests immediately in front of the corresponding stud 52, so that upon forward movement of the corresponding handle member 27, the corresponding lug 49 is prevented from dropping into the corresponding notch 48, thus permitting withdrawal of the handle member. Were the nickel not present, the arm 50 would be free to rock downwardly so that lug 49 would drop into engagement with notch 48 and prevent such movement. Thus, it will be observed that upon the deposit of a suitable coin in any of the coin slots, the corresponding handle 27 may be manipulated to cause delivery of an envelop from the corresponding envelop hopper through the corresponding opening 30. The rear portion of each of the cams 47 is arranged on a slight upward incline, as shown, so that continued forward movement of the corresponding bracket will cause engagement with the corresponding lug 49 to swing the corresponding arm 50 upwardly toward the end of such movement and thus release and discharge a coin suspended by the corresponding lug 53.

Each of the brackets 35 also carries a cam member 61 coöperating with a cam member 62 formed on the under side of a corresponding arm 63 pivotally mounted in the casing at 63'. Each of the arms 63 corresponding with the two hoppers containing a nickel's worth of stamps is provided with an upwardly and a forwardly projecting finger 64 pivoted thereto at 65 and provided with a stop 66 engaging against the forward edge thereof, to permit swinging of the finger 64 in one direction only. A spring 67 is connected at its forward end to the lower portion of finger 64 and at its rearward end to an arm 68 formed on the arm 50, said spring 67 normally holding finger 64 to move in unison with arm 50 but permitting of yielding of said finger in case of necessity. The upper forward end of finger 64 is arranged to operate through an opening 69 into coin space 54. The arrangement is such that upon forward movement of either of the handles corresponding to the nickel hoppers, the corresponding finger 64 will be rocked out into the corresponding

coin space and intercept a coin such as coin 60' to prevent the same from being discharged from the coin chute simultaneously with the coin resting upon lug 53.

5 A coin thus discharged will descend until intercepted by a pin 70 projecting through an opening 71 and carried by a rocker plate 72 having an inwardly extending arm 73 provided with a cam member 74 adapted to engage with a cam surface 75 on the forward lower portion of the corresponding cam member 47 adjacent the end of the forward stroke of the corresponding bracket 35, thus depressing the arm 73 and throwing the corresponding pin 70 into the path of such a coin and holding the same there until the withdrawal of the corresponding bracket 35. Upon withdrawal of the corresponding bracket 35, the corresponding rocker plate 20 72 is returned to normal position through the influence of a spring 76 and a corresponding pin 77, projecting through a corresponding opening 78, is simultaneously rocked to intercepting position to intercept 25 a coin thus released by the retraction of the corresponding pin 70. A glass sight plate 79 is arranged in the front plate 55 opposite the positions of pins 70 and 77, so that a coin intercepted by pin 77 will be visible 30 from the exterior thus tending to prevent dishonest use of the machine. By this arrangement, it will be observed that upon operation of either of the nickel slides, the corresponding nickel will be deposited on the 35 corresponding pin 77 in plain view. Should a penny or token smaller than a nickel be deposited, the arrangement of the parts is such that it will immediately pass lug 53 and rest upon the top of the nickel suspended by 40 pin 77 whereupon the next operation will disclose the same, should further pennies or small tokens be deposited they would strike the penny arrested and roll laterally and descend into the money drawer 13.

45 The mechanism for dispensing a dime's worth of stamps is substantially the same as that for dispensing a nickel's worth, except that special provision is made to insure the discharge of a dime from its initial position. I have found from experience that in 50 case a dime is slightly sticky, it being much lighter than a nickel, is likely to stick in the coin chute and thus impair the reliability of the machine. To prevent this, I remove 55 the finger 64 from the corresponding arm 63 and substitute therefor an arm 80 provided with a stop pin 81 and held by a spring 82, as indicated in Figs. 6 and 8. To the inner end of each of the arms 80, I pivot a finger 60 83 at 84 in position to project outwardly through opening 85 in the front of casing 11. Each of the fingers 83 is provided with a depending arm 86 carrying an adjustable set screw 87 on which is mounted a combined 65 lock and stop nut 88 adapted to contact with

the upper side of the corresponding arm 68. By this arrangement, upon initial movement of the corresponding handle 27, the finger 83 will be thrown outwardly sufficiently to intercept a coin by the action of arm 63. Then, at the end of the movement of the corresponding cam 47, the corresponding arm 50 is operated to give the corresponding finger 83 an additional movement which will effectually discharge a dime thus suspended. The other parts of the mechanism for dispensing a dime or ten cents' worth of stamps is identical with that for dispensing a nickel or five cents' worth, and needs no further description, the same reference numerals having been applied to the same parts in each instance.

The machine disclosed will be found to be a simple and efficient one for the purpose which is reliable and durable in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A vending machine comprising a casing provided with a coin chute; a reciprocating slide arranged to discharge articles from said casing; a cam member operatively connected with said slide; a locking dog arranged to engage said member after initial movement thereof to prevent discharging operation, said dog being arranged to traverse said coin chute in effecting such movement, said cam being arranged to reversely move said dog; and a stop in said chute arranged to arrest a coin in position to prevent engaging movement of said dog, substantially as described.

2. A vending machine comprising a casing provided with a coin chute; a reciprocating slide arranged to discharge articles from said casing; a cam member operatively connected with said slide; a locking dog arranged to engage said member after initial movement thereof to prevent discharging operation, said dog being arranged to traverse said coin chute in effecting such movement, and said cam being arranged to reversely move said dog; and a stop on said dog projecting into said chute, substantially as described.

3. A vending machine comprising a casing provided with a coin chute; a reciprocating slide arranged to discharge articles from said casing; a notched cam member operatively connected with said slide; a

locking dog arranged to engage said member after initial movement thereof to prevent discharging operation, said dog being arranged to traverse said coin chute in effecting such movement, and said cam being arranged to reversely move said dog; and a stop on said dog projecting into said chute arranged to engage a coin to prevent engaging movement of said dog, substantially as described.

4. A vending machine comprising a casing provided with a coin chute; a reciprocatory slide arranged to discharge articles from said casing; a notched cam member operatively connected with said slide; a locking dog arranged to engage the notch in said member after initial movement thereof to prevent discharging operation, said dog being arranged to traverse said coin chute in effecting such movement, and said cam being arranged to reversely move said dog; and a stop in said chute arranged to arrest a coin in position to prevent engaging movement of said dog, substantially as described.

5. A vending machine comprising a casing provided with a coin chute; a reciprocatory slide arranged to discharge articles from said casing; a notched cam member operatively connected with said slide; a locking dog arranged to engage the notch in said member after initial movement thereof to prevent discharging operation, said dog being arranged to traverse said coin chute in effecting such movement, and said cam being arranged to reversely move said dog; a stop in said chute arranged to arrest a coin in position to prevent engaging movement of said dog; and means operable by said reciprocatory slide for discharging an arrested coin, substantially as described.

6. A vending machine comprising a casing provided with a coin chute; a reciprocatory slide arranged to discharge articles from said casing; a notched cam member operatively connected with said slide; a locking dog arranged to engage the notch in said member after initial movement thereof to prevent discharging operation, said dog being arranged to traverse said coin chute in effecting such movement, and said cam being arranged to reversely move said dog; a stop in said chute arranged to arrest a coin in position to prevent engaging movement of said dog; means operable by said reciprocatory slide for discharging an arrested coin; and means compelling complete movement of said reciprocatory slide in each direction before permitting return movement thereof, substantially as described.

7. A vending machine comprising a casing; a pair of vending hoppers arranged in said casing; a spring held reciprocatory

slide arranged under each hopper; a delivery member secured to each slide and operating across the bottom of the corresponding hopper, there being a discharge opening corresponding to each delivery member; coöperating brackets carried by said slides and traveling adjacent each other, there being registering notches in said brackets; a pivoted finger having a stud operating in said notches to prevent simultaneous movements of said brackets; a ratchet bar carried by each slide; a double acting spring pawl coöperating with each ratchet bar to compel complete movement of each slide in each direction before return; and coin controlled means for preventing or permitting operation of said slides, substantially as described.

8. A vending machine comprising a casing; a pair of vending hoppers arranged in said casing; a spring held reciprocatory slide arranged under each hopper; a delivery member secured to each slide and operating across the bottom of the corresponding hopper, there being a discharge opening corresponding to each delivery member; coöperating brackets carried by said slides and traveling adjacent each other, there being registering notches in said brackets; a pivoted finger having a stud operating in said notches to prevent simultaneous movements of said brackets; a ratchet bar carried by each slide; a double-acting spring pawl coöperating with each ratchet bar to compel complete movement of each slide in each direction before return; a notched cam on each bracket; a spring-held dog riding on each cam; a stop lug on each dog, there being a coin chute in said casing traversed by each lug; and means in each chute coöperating with said lug for temporarily holding a coin in position to prevent operation of said dog, said cam being arranged to operate said dog to release said coin, substantially as described.

9. A vending machine comprising a casing; a pair of vending hoppers arranged in said casing; a spring-held reciprocatory slide arranged under each hopper; a delivery member secured to each slide and operating across the bottom of the corresponding hopper, there being a discharge opening corresponding to each delivery member; coöperating brackets carried by said slides and traveling adjacent each other, there being registering notches in said brackets; a pivoted finger having a stud operating in said notches to prevent simultaneous movements of said brackets; a ratchet bar carried by each slide; a double-acting spring pawl coöperating with each ratchet bar to compel complete movement of each slide in each direction before return; a notched cam on each bracket; a spring-held dog riding on each cam; a stop lug on each dog, there being a coin chute in said casing traversed by each lug; and means in each chute coöperating with said lug for temporarily holding a coin in position to prevent operation of said dog, said cam being arranged to operate said dog to release said coin, substantially as described.

lug on each dog, there being a coin chute in said casing traversed by each lug; means in each chute coöperating with said lug for temporarily holding a coin in position to prevent operation of said dog, said cam being arranged to operate said dog to release said coin; a second cam on each bracket; and a spring-held finger operable by said second cam to stop passage of coins through

the corresponding chute, substantially as 10 described.

In testimony whereof I have signed my name to this specification in the presence of two subscribing witnesses.

THOR W. PETERSEN.
